BOTTLE CARRIER

Ralph W. Stevenson, Grand Rapids, Mich., assignor, by mesne assignments, to Metal Carrier Corporation, Grand Rapids, Mich., a corporation of Michigan

Application October 11, 1948, Serial No. 53,773

10 Claims. (Cl. 220—21)

1

My invention relates to an improved bottle carrier adapted to hold a plurality of bottles for transportation and storage.

In industries, such as the soft drink industry, where bottles are transported and stored, it has heretofore been the common practice to handle the bottles in wooden carriers each of which defines a plurality of bottle-receiving compartments. This practice has developed because such carriers have to date demonstrated ability to withstand the shocks and blows incident to handling superior to the ability of other practical carriers.

Despite this superior ability, wooden carriers are bulky and heavy and are relatively easily damaged in use. Moreover, the wood absorbs moisture, syrups, and like substances to which the carriers are exposed and can be cleaned only with difficulty. As a consequence the weight of the carriers is further increased and they present an unsightly and unsanitary appearance that detracts from the sales of the bottles they contain. These difficulties, together with the tendency of wooden carriers to damage clothing when handled, have prevented the use of such carriers in homes and have rendered more difficult their use commercially.

Efforts to provide a practical metal bottle carrier have heretofore failed, either by reason of the inability of the metal to withstand the blows and shocks incident to handling, or by reason of the inability of the carrier to protect the bottles from breakage under these shocks and blows.

In accordance with the present invention an improved bottle carrier which can be made of light weight metal, such as aluminum alloy, is provided. This carrier is lighter in weight and less bulky than conventional wooden bottle carriers and efficiently protects the bottles against damage resulting from blows and shocks. Moreover, the carrier itself is highly resistant to blows and shocks and has demonstrated ability to handle a considerably greater number of blows than the carriers heretofore used. All this is accomplished in an attractive carrier that is readily washed and presents a clean, sanitary appearance and is suitable for use in storing bottles.

It is therefore a general object of the present invention to provide an improved bottle carrier.

More specifically it is an object of the present invention to provide an improved bottle carrier capable of being constructed of light metal, such as aluminum, and presenting an attractive structure which is readily cleaned.

Another object of the present invention is to

2

provide an improved bottle carrier capable of retaining a plurality of bottles and protecting the same from damage during handling.

Another object of the present invention is to provide an improved bottle carrier capable of withstanding repeated blows and shocks without damage.

Yet another object of the present invention is to provide an improved bottle carrier suitable for transporting and storing a plurality of bottles as a unit.

The novel features which I believe to be characteristic of my invention are set forth with particularity in the appended claims. My invention itself, both as to its organization and mode of operation, together with further objects and advantages thereof, may best be understood by reference to the following description taken in connection with the accompanying drawing, in which:

Figure 1 is a view in perspective of a bottle carrier constructed in accordance with the principles of the present invention;

Figure 2 is a fragmentary side elevational view of a pair of bottle carriers like that of Figure 1 stacked on top of each other;

Figures 3 and 4 are cross-sectional views through axes 3—3 and 4—4, Figure 1;

Figure 5 is an enlarged fragmentary broken away view of a portion of the upper edge of the wall of the carrier of Figure 1 showing the reinforcing rod provided for the same;

Figure 6 is a fragmentary cross-sectional view through axis 6—6, Figure 2;

Figure 7 is an enlarged fragmentary top plan view of the bottle carrier of Figure 1; and,

Figure 8 is a fragmentary enlarged view like Figure 4 but with the spacings between the struts and the wall and the separators exaggerated to show more clearly the construction thereof.

Referring now to Figures 1 and 7, the bottle carrier comprises a sheet metal base or bottom 10 surrounded by bottle-retaining side and end walls 1 and 2 to define a basket. A plurality of separators 17 extend lengthwise of the carrier to define a plurality of bottle-receiving rows. These rows are broken up into a series of bottle-retaining compartments by the transvers members defined by struts 16 and 21 and sleeves 22.

The separators 17 are preferably of thin light sheet metal, such as an aluminum alloy. A plurality of longitudinal indentations 17a, Figure 3, extend along each separator to increase the rigidity of the same. The rolled upper edges of

separators 17 are designated by reference numeral 20.

Each separator is swingingly attached to the bottom 10 by the hinge defined by rod 19 and the cooperating segmental rib portions 15 of the base 10 and hook portions 18 of the separator. As best seen in Figure 4, the portions 15 of the base 10 are formed by drawing the base 10 upwardly in upstanding segmental ribs relative to the general level of the base and capable of receiving rods 19. The hook portions 18 of the separators 17 are formed by bending over the lower edges of these separators about the rods 19.

Swinging movements of the separators 17 about the hinges defined by rods 19 are opposed by struts 21 and the resilient sleeves 22. The former are loosely received in openings 1a, Figure 8, in the side walls 1 and are anchored relative thereto by the headed portions 21a which bottom against the outside faces of the opposite side walls 1. Thus each side wall restrains the struts against movement in one direction and together they prevent movements in either direction. The struts 21 are received in the aligned strut-receiving apertures or openings 1b, Figures 4 and 8, formed in the separators 17 adjacent their upper edges. Each of these openings is somewhat larger in size than the strut to provide a relatively loose fit permitting limited swinging movements of the separators without interference.

Resilient sleeves 22 of rubber or rubber-like material surround each strut 21 in the region between each pair of adjacent separators and between each end separator and the side walls 1. These sleeves fit loosely about the struts 21 and bottom against the adjoining separators 17 or side wall 1 as the case may be.

The sleeves 22 perform the dual function of forming resilient members against which the bottles strike when blows are struck in the direction of orientation of the separators 17 and of forming resiliently yieldable elements urging the separators 17 to the upright position. When blows or shocks are imparted to the carrier in the direction of orientation of the struts, the separators 17 are thus permitted resiliently to yield and take up the impact otherwise transmitted to the bottles.

Auxiliary struts 16 are vertically aligned with struts 21 but are adjacent the lower portions of the carrier. These struts are loosely received in aligned apertures 17c formed in the separators 17 and are likewise loosely received in the apertures or openings 1b, Figure 8, formed in the side walls 1.

At their upper edges, the side walls 1 carry a pair of complementary rods 5, Figures 3 and 5. Each of these rods is U-shaped and extends half way about the rectangular shaped upper edge of the walls 1 and 2. The ends of these rods face each other at the center of the end walls 2 and are received in sleeves 7.

The rods 5 reinforce the walls 1 and 2 and for that purpose are preferably constructed of steel. The upper edges of these walls are bent over at 3 to encircle these rods and snugly receive the same.

As shown best in Figure 5, the ends of rods 5 are normally in spaced relationship with each other in the sleeves 7. This permits the opposite sides 1a and 1b, Figure 1, of wall 1, to flex relative to each other under the impact of blows without tending to collapse the reinforcing rods 5.

A single reinforcing rod 6, of steel or like ma-

terial, extends about the lower edge of walls 1 and 2. This rod is snugly received by the turned over lower edge of the walls as indicated at 4, Figure 8.

The lower edge of the walls 1 and 2 is further reinforced by the upstanding skirt 11 formed on bottom 10. As indicated in the figures, this skirt extends above the level of openings 12 and is crimped over about the same, thus securely retaining the bottom and the walls relative to each other.

The walls 1 and 2 are formed of a single sheet of light metal, such as aluminum alloy, extending entirely around the carrier. At the center of one end wall 2, where the two ends meet, they are overlapped as shown in Figure 6. An opening is formed in this overlapped section and portion 2a of the wall is crimped over the portion 2b to secure the same in position.

Hand openings are provided in the opposed end walls 2 as shown in Figures 1 and 3. As best seen in the latter view, the wall 2 is bent outwardly at 8 to define these openings and a tubular insert 9 placed therein and crimped over at 5 to be anchored in position.

The separators 17 have triangular cut-out portions crimped over at 17d to define space for the fingers of a person handling the carrier.

The bottom 10 is formed of relatively thin sheet metal, such as aluminum alloy, and is formed with a plurality of apertures or openings 10a having crimped over rims 14. One aperture is centrally disposed in each bottle-receiving compartment as shown in Figure 7. The portions of the bottom adjacent each rim 14 are embossed upwardly as shown at Figure 2 to define an annular portion rising above the general plane of the bottom 10.

The rims 14 are adapted to overlay only the outer peripheries of the bottle caps C when a plurality of carriers are stacked as shown in Figure 2. This causes each carrier to seat on the bottles of the next lower carrier and imparts stability to the stack so formed. That is, any forces tending to shift one carrier relative to another are opposed by the seating engagement of the adjacent carriers and bottles.

The embossed portion 13 adjacent each rim 14 defines a dome to be received in the cupped base of the bottle as shown in the broken away portion of Figure 2 where a bottle B is shown in phantom as received over the dome. This centers each bottle in its compartment under normal conditions and positions it in registry with the corresponding bottle of the next higher carrier, thereby causing the cap of each bottle to register with the seat defined by the corresponding rim 14 of the next higher carrier.

The bottom 10 may be of relatively thin flexible construction since it is reinforced by the struts 16 and 21 and by the separators 17. These elements cooperatively define a truss which is connected to the bottom 10 by the rods 19 and which reinforces the bottom 10 to take up the stress that would otherwise flex the bottom.

Extensive tests and actual operation have demonstrated that the bottle carrier of the present invention is capable of withstanding a greater number of blows than the carriers heretofore available and, in addition, protects the bottles against damage. In one test, for example, this carrier withstood 1500 blows of the same intensity that demolished a good quality existing carrier at 150 blows.

In addition to the functions described above

the struts 16 act to support the bottom portions of the bottles in adjacent compartments and, moreover, act to retain the bottles in the carrier when the same is tilted.

In the appended claims I have used the term "bottoming against said separators" to define the relationship between the sleeves 22 and the separators 17 whereby the former abut the latter to oppose swinging movements thereof.

While I have shown and described a specific embodiment of my invention it will, of course, be understood that various modifications and alternative constructions may be used without departing from the spirit and scope thereof. I therefore intend by the appended claims to cover all such modifications and alternative constructions as fall within the true spirit and scope of my invention.

What I claim as new and desire to secure by Letters Patent of the United States is:

1. In a bottle carrier of the type having a bottom and a bottle retaining wall, a plurality of separators disposed in said carrier to define a plurality of bottle receiving rows, said separators each being cut short of the ends of said carrier and supported from the bottom thereof for swinging movements about axes parallel to the direction of orientation of said separators, said separators having aligned strut-receiving openings adjacent their upper edges, struts loosely received in said openings, said struts being oriented in direction substantially transverse to said separators to define a plurality of bottle-receiving compartments, and resilient elements surrounding each of said struts in the regions between adjacent separators and between the outermost separators and said wall and bottoming against said separators and said wall.

2. In a bottle carrier of the type having a bottom surrounded by a wall to define a bottle retaining basket, the improvement which comprises a plurality of separators disposed in said basket to define a plurality of bottle-receiving rows, the lower edges of the separators being hingedly secured to the bottom for swinging movement about axes parallel to the direction of the separators, said separators having aligned strut-receiving openings adjacent their upper edges, struts loosely received in said openings, said struts being oriented in direction substantially transverse to said separators to define a plurality of bottle-receiving compartments, and resilient elements surrounding each of said struts in the regions between the adjacent separators and between the outermost separators and said wall and bottoming against said separators and said wall.

3. A bottle carrier of the type having a bottom and a peripheral bottle-retaining wall, the improvement which comprises a plurality of separators disposed in said basket to define a plurality of bottle-receiving rows, hinge means adapted to support each of said separators from the bottom of said carrier for swinging movements about an axis parallel to the orientation of said separators, said separators having aligned strut-receiving openings adjacent said bottom and adjacent their upper edges, struts loosely received in said openings and extending across said basket in direction substantially transverse to the orientation of said separators to define a plurality of bottle-receiving compartments, and resilient elements each surrounding one of the struts in said last mentioned openings in the region between adjacent separators and between the outermost sepa-

rators and the retaining wall, the elements bottoming against the separators and the retaining wall.

4. A bottle carrier of the type having a bottom and defining a bottle-retaining basket, the improvement which comprises a plurality of separators disposed in said basket to define a plurality of bottle-receiving rows, hinge means adapted to support each of said separators from the bottom of said carrier for swinging movements about an axis parallel to the orientation of said separators, said separators having aligned strut-receiving openings near their upper edges, struts loosely received in said openings and extending across the basket in direction substantially transverse to the orientation of said separators to define a plurality of bottle-receiving compartments, and resilient elements each surrounding one of said struts in the region between adjacent separators and between the outermost separators and the side wall of the bottle-retaining basket, the elements bottoming against the separators and the side wall.

5. In a bottle carrier of the type having a bottom and edge wall defining a bottle-retaining basket, the improvement which comprises a plurality of separators disposed in said basket to define a plurality of bottle-receiving rows, the lower edges of the separators being hingedly secured to the bottom for swinging movements about an axis parallel to the orientation of said separators, and resilient elements bottoming against the separators and against the outermost separators and the edge wall yieldably supporting the separators in erect position for swinging movements under the impact of said bottles when said carrier is struck.

6. In a bottle carrier of the type having elements including a bottom defining a bottle retaining basket, a plurality of separators extending in one direction across said basket to define a plurality of bottle-receiving rows, hinge means adapted to support each of said separators from the bottom of said carrier for swinging movements about an axis parallel to the orientation of said separators, and a plurality of spacers extending across said basket in direction substantially transverse to the orientation of said separators, thereby defining bottle-receiving compartments, said spacers carrying compressible, resilient elements supporting said separators for yielding movements in the direction of said spacers to permit movements of said spacers under the impact of the bottles when said carrier is struck.

7. In a bottle carrier of the type having bottom and wall elements defining a bottle retaining basket, a plurality of separators extending in one direction across said basket to define a plurality of bottle-receiving rows, the lower edges of the separators being hingedly secured to the bottom for swinging movements about an axis parallel to the orientation of said separators, said separators having a plurality of aligned strut-receiving apertures, struts in the apertures extending across said basket in direction substantially transverse to the orientation of said separators, and resilient elements each surrounding one of said struts in the region between adjacent separators and bottoming against said separators and against the outermost separators and the wall.

8. In a bottle carrier for bottles having caps and cupped bases, a bottom, a wall surrounding said bottom to define a bottle retaining basket, a plurality of separators hingedly attached to said bottom and extending across said basket to

define a plurality of bottle retaining rows, said separators having aligned strut-receiving openings near their upper edges, struts anchored to said wall and received loosely in said openings and in substantially transverse orientation relative to said separators to define bottle-receiving compartments, resilient sleeves each surrounding one of said struts in the region between adjacent separators and bottoming against said separators, said bottom having a plurality of apertures, one for each of said compartments and adapted partially to fit over the caps of the bottles of a next lower carrier, the marginal portions of said apertures being embossed upwardly to define upraised annular portions to be received in the cupped bases of said bottles to retain the same in said carrier.

9. A bottle carrier having a bottom member with upturned edge portions, a side wall defining member received on said edge portions and affixed thereto by crimped-over draw-holes, reinforcing rods surrounding the lower and upper portions of said wall defining member, said member being wrapped about said rods to secure the same thereto, aligned separators hingedly secured to said bottom member, and means yieldably supporting said separators in an upright position.

10. In combination, a bottle-retaining basket defined by a relatively flexible bottom surrounded by a bottle-retaining wall, a plurality of separators extending longitudinally of the basket and each anchored along its length to the bottom thereof by hinge means permitting said separators to swing about longitudinal axes, and a plurality of resilient elements extending cross-wise of the separators to define bottle pockets in conjunction therewith, the elements bottoming

against the separators and the outermost separators and the wall to sustain the separators in upright position and define a bottom-reinforcing truss.
